[57] CLAIM

The ornamental design for a bicycle tire, as shown and described.

DESCRIPTION

FIG. 1 is a perspective view of a bicycle tire showing my new design, being understood that the tread pattern is repeated throughout the circumference of the tire as shown schematically by solid lines; FIG. 2 is a side elevational view of the side shown, the opposite side being a mirror image; FIG. 3 is an end elevational view thereof; and FIG. 4 is an enlarged fragmentary plan view showing the tread pattern thereof in greater detail.
